CLAIM

The ornamental design for a surgical instrument rest, as shown and described.

DESCRIPTION

FIG. 1 is a perspective view of a surgical instrument rest, showing my new design;

FIG. 2 is a top plan view thereof;

FIG. 3 is a front elevational view thereof;

FIG. 4 is a bottom plan view thereof;

FIG. 5 is an end elevational view thereof; the opposite end being identical thereto;

FIG. 6 is a cross sectional view taken along line 6—6 of

FIG. 1; and

FIG. 7 is a rear elevational view thereof.

FIG. 1

FIG. 2

FIG. 3

FIG. 4

FIG. 7
